[57] CLAIM

The ornamental design for a television receiver, as shown and described.

DESCRIPTION

FIG. 1 is a front, top and right side perspective view of a television receiver showing our new design;

FIG. 2 is a front elevational view thereof;

FIG. 3 is a right side elevational view thereof;

FIG. 4 is a top plan view thereof;

FIG. 5 is a rear elevational view thereof;

FIG. 6 is a bottom plan view thereof;

FIG. 7 is a front, top and right side perspective view of a modified embodiment of the television receiver shown in FIG. 1;

FIG. 8 is a front elevational view thereof; and

FIG. 9 is a right side elevational view thereof.

The top, rear and bottom views of the second embodiment are identical to those shown in FIGS. 4, 5 and 6, respectively.

FIG. 1

FIG. 2

FIG. 3

FIG. 4

FIG. 5

FIG. 6

FIG. 7

FIG. 8

FIG. 9
